UNITED STATES PATENT OFFICE

2,105,157

ASHTRAY AND COASTER

Thomas R. Moss, Dyersburg, Tenn.

Application March 26, 1937, Serial No. 133,282

8 Claims. (Cl. 131—59)

This invention relates to ash receivers, and particularly to ash receivers designed for use as a permanent part of tables, arms of chairs or similar supporting surfaces.

5 An important object of the invention is to provide an ash receiver of this character including a removable receptacle, the receptacle being supported directly under the supporting surface and constructed in such a way that cigar or cigarette ashes may be readily deposited therein.

10 Another object of the invention is the provision of means for removably securing the receptacle to the supporting section of the ash receiver, due consideration being given to the strength and durability of the securing means, to insure a close fit between the receptacle and supporting section of the ash receiver.

15 With the foregoing and other objects in view, which will appear as the description proceeds, the invention resides in the combination and arrangement of parts and in the details of construction hereinafter described and claimed, it being understood that changes in the precise embodiment of the invention herein described, may be 20 made within the scope of what is claimed, without departing from the spirit of the invention.

25 Referring to the drawing:

Figure 1 is a vertical sectional view through an ash receiver constructed in accordance with the invention, and illustrating the ash receiver as supported within an opening of a supporting surface.

Figure 2 is a plan view thereof.

30 Figure 3 is a bottom view of the ash receiving receptacle.

Figure 4 is a fragmental elevational view illustrating the yieldable securing means employed in securing the receptacle to the supporting section of the ash tray.

35 Referring to the drawing in detail, the support for the ash tray is indicated by the reference character 5, the support being provided with an opening for the reception of the supporting section or ring of the top of the ash tray, indicated by the reference character 6.

The top of the ash tray is formed with a central opening through which ashes, cigarette stubs and the like may be dropped into the receptacle 11, supported thereunder. Depressions 17 are 40 also formed in the top of the tray, in which cigarettes and cigars may be placed.

45 This supporting section is formed with an annular flange 7 adapted to fit against the upper surface of the support 5, as clearly shown by Figure 1 of the drawing, to prevent the support

from being forced through the opening of the supporting surface, while the ash tray is in use. Forming a part of the tray 6, is a downwardly extended flange 8, which is of a width to extend an appreciable distance below the support 5. Yieldable tongues indicated by the reference character 9 are stamped from the flange 8, and are formed with lugs 10 adapted to fit under the support 5, as shown by the drawing, to secure the supporting section 6 of the ash tray within the 10 opening in which the ash tray is positioned.

5 The reference character 11 designates the removable ash receiving receptacle, forming a part of the ash tray. This receptacle 11 is formed with an offset upper end of a diameter to receive 15 the lower end of the flange 8 of the supporting section 6.

20 Openings are formed in the flange 8, at points directly below the lower surface of the support 5, for the reception of the right-angled ends 12 of the yieldable securing member 13. This securing member 13 embodies a length of wire material having angular end portions 14 which are disposed at oblique angles with respect to the main portion of the securing wire, the upwardly 25 extended portions 14 being extended in opposite directions. The ends 15 of the upwardly extended portions 14 are extended inwardly, lending resiliency to the securing member. Thus it will be seen that due to this construction, a slight 30 downward pull on the receptacle 11, will cause the securing wire 13 to move downwardly, whereby the receptacle 11 may be readily removed by sliding the receptacle laterally.

35 When it is desired to replace the receptacle 11, the receptacle is slid into position between the member 13 and lower edge of the downwardly extended flange 8, whereupon the resiliency of the securing member will securely hold the receptacle in place.

40 It might be further stated that the receptacle 11 has its bottom inclined upwardly towards the sides thereof, providing surfaces to ride over the member 13, facilitating the positioning of the receptacle.

45 Having thus described the invention, what is claimed is:

1. In an ash receiver, a supporting section, a receptacle positioned against the supporting section, said supporting section having openings, and a securing wire positioned against the receptacle, the ends of the securing wire extending upwardly at oblique angles with respect to the bottom of the receptacle, said ends having right-angled portions fitted in the openings of the supporting sec- 55

tion, securing the receptacle to the supporting section.

2. In an ash receiver, a supporting section, a receptacle positioned against the supporting section and adapted to receive material, said supporting section having openings, and a securing member embodying a length of yieldable wire material fitted against the bottom of the receptacle, the ends of the securing wire being adapted to extend into the openings for removably securing the receptacle to the supporting section.

3. In an ash receiver, a supporting section adapted to be fitted in an opening of a supporting surface, a receptacle having an offset portion at its upper edge, the lower end of the supporting section being fitted in the offset portion of the receptacle, and a yieldable supporting wire extending across the bottom of the receptacle, the ends of the wire engaging the supporting section, removably securing the receptacle to the supporting section.

4. In an ash receiver, a supporting section adapted to be fitted in an opening of a supporting surface, the lower ends of the supporting section extending below the lower surface of the supporting section and having openings, a receptacle fitted against the lower edge of the supporting section, and a supporting wire fitted against the bottom of the receptacle, the ends of the wire extending upwardly at oblique angles with respect to the bottom of the receptacle, and disposed in opposite directions, and portions of the supporting wire extending into the openings removably securing the wire and receptacle to the supporting section.

5. In an ash receiver, a supporting section, a receptacle fitted against the supporting section,

the bottom of the receptacle being inclined, and a supporting wire fitted against the bottom of the receptacle, portions of the wire extending upwardly at oblique angles with respect to the bottom of the receptacle, and in opposite directions, the ends of the wire contacting with the supporting section, removably securing the wire and receptacle to the supporting section. 5

6. In an ash receiver, a supporting section extended through an opening in a supporting member, a receptacle fitted against the lower end of the supporting section, and a member for removably securing the receptacle to the supporting section, said securing member including a length of wire material, the ends thereof extending upwardly and being disposed at oblique angles with respect to the bottom of the receptacle, said ends of the supporting member being removably connected with the supporting section, removably securing the receptacle to the supporting section. 10 15

7. A tray structure adapted to be secured to a perforate object, comprising a top member having a flange portion and a collar portion, a cup member adapted to engage said collar portion, 25 and an interlocking member adapted to engage said collar portion and removably lock the same to said object and frictionally engage said cup member for removably locking the same to said collar. 30

8. The combination with a two part tray member, of a substantially Z-shaped interlocking member adapted to removably secure the two parts of the tray members together and removably lock one of the members to an object. 35
